VANITY LAVATORY TOP

Charles R. Margolies, Oreland, Pa., assignor to Madison Products Incorporated, Madison, N.J., a corporation of New Jersey

Filed Dec. 9, 1959, Ser. No. 58,619

Term of patent 14 years

(Cl. D4—2)

Fig. 1.

Fig. 2.

Fig. 3.

FIG. 4.

FIG. 5.

FIG. 1 is a front perspective view taken from the top and right side of a vanity lavatory top embodying my new design;

FIG. 2 is a front elevation view thereof;

FIG. 3 is a right side elevational view thereof;

FIG. 4 is a rear perspective view taken from the bottom; and

FIG. 5 is a top plan view thereof.

The dominant features of the design reside in the portions shown in full lines, said portions being characterized by the specifically contoured upright splash panel in association with the particular bowl top as best shown in FIGS. 1 and 5.

I claim:

An ornamental design for a vanity lavatory top as shown and described.
